HUGO E. GRIESHABER, OF NEW LONDON, CONNECTICUT, ASSIGNOR TO ELECTRIC BOAT COMPANY, OF GROTON, CONNECTICUT, A CORPORATION OF NEW JERSEY

EMERGENCY FUEL-TANK SEA VALVE

Application filed June 17, 1929. Serial No. 371,440.

This invention relates to submarine boats, and more particularly to valves used in case of emergency for blowing water or oil from the fuel tanks.

5 It is the common practice on submarine boats to carry fuel in ballast tanks, particularly when it is desired to obtain a long cruising radius and, after this fuel is used, to again use the ballast tanks for water to give the boat 10 the maximum amount of buoyancy on the surface. The oil adheres to the sides of the tank and when the tank is filled with water, which is required to submerge the vessel, the oil leaks out past the valves provided for blowing 15 out the compartment, if large valves are used, and causes a slick on the surface which is easily picked up by the enemy and, for this reason, is a source of great danger in time of war.

20 Due to the impossibility of preventing this leakage of oil referred to, when using large Kingston valves of present type, the present practice is to use small valves for blowing out the fuel tanks since the small valves are more 25 easily controlled to prevent leakage of oil. The use of small valves is, however, highly objectionable in some respects. In case of emergency it is frequently of vital importance that the ballast tanks be blown out in the

30 shortest possible time to provide additional buoyancy for the boat. At such times the small valves are highly objectionable. I have found that, by providing suitable sealing means associated with the valve, it is entirely 35 feasible to utilize large Kingston valves for blowing out the ballast tanks, including the fuel tanks, in case of emergency, and also to avoid any leakage of oil which would give rise to the objectionable slick on the surface 40 above referred to. One of the main objects of my invention is to provide simple and efficient means for effectively sealing a valve of the character referred to, so as to eliminate possibility of leakage about the same from 45 within the tanks of the submarine boat. A further object is to provide sealing means which can be readily applied to a Kingston valve of known construction without necessitating any changes in construction thereof. 50 Further objects and advantages of my in-

vention will appear from the detailed description.

In the drawings:

Figure 1 is a side view of a submarine boat illustrating diagrammatically my invention 55 as applied thereto; and

Figure 2 is a fragmentary sectional view through the hull and valve ring and associated parts, on an enlarged scale, showing my invention as applied, parts being shown 60 in elevation and the operating cylinder for the valve being shown in section.

I have illustrated my invention as applied to a submarine boat B of known type provided with a plurality of ballast tanks 1 used for storing fuel. Each of these tanks is provided with an opening 3 through the hull 2 to the sea. A valve ring 4 is disposed in this opening and is provided at its outer end with an outer peripheral flange 5 suitably secured to a base ring 6 which is suitably secured to the outer face of hull 2 about opening 3. Ring 4 is provided, in its outer end, with a valve seat 7 in which seats a Kingston valve 8. This valve opens outwardly of hull 2 and is provided with an inwardly extending stem 9 slidable through a guide collar 10 supported by arms 11 carried by ring 4.

Valve stem 9 extends into a cylinder 10 80 disposed within tank 1, through a suitable stuffing box 13. A piston 14 is suitably secured to the inner end of valve stem 9, as by being integral therewith, and operates in cylinder 12. A pressure inlet pipe 15 opens 85 into cylinder 12 beyond the inner side of piston 14 and is provided with a check valve 16 which opens toward the cylinder. An outlet pipe 17 opens into the cylinder 12 in the plane of piston 14 when valve 8 is closed, and is provided with a check valve 18 which opens outwardly away from the cylinder. An expansion coil spring 19 is confined 90 between piston 14 and the outer head of the cylinder, being disposed about valve stem 9, this spring acting normally to hold valve 8 seated. Compressed air may be supplied to pipe 15 in a suitable manner, as by means of a manifold 20 controlled by a valve 21, this manifold being connected to air flasks or 95 100

any other suitable supply of air under pressure in a known manner. The manifolds 20 are preferably disposed in end compartments 22 and 23 of the hull 2, these compartments being salvage or rescue compartments.

5 The valve itself is, in general, of known construction and need not be further illustrated nor described in detail. When air is admitted through pipe 15 valve 8 is projected outwardly into open position and, 10 when piston 14 moves beyond pipe 17 compressed air passes through this pipe and is discharged therefrom into the upper portion of tank 1 so as to blow the oil or water therefrom.

15 The valves 8 are emergency valves and are to be used only in time of emergency when it is necessary to blow the oil or water out of the ballast tank 1. As a general rule, when 20 such an emergency arises, it is of vital importance that the ballast tank be emptied with the least possible delay. By using relatively large valves 8 the ballast tank can be emptied quickly but, under present practice, these valves are open to objection of oil 25 leakage above noted. In order to overcome this objection I provide a sealing disc 24 which extends over the outer face of valve 8 in contact therewith, and secure the peripheral portion of this disc to flange 5 of ring 4, by means of a clamping ring 25 which seats upon the outer face of the disc, and securing screws 26 which pass through ring 25 and screw into flange 5. Ring 25 cooperates with 30 flange 5 to securely clamp the disc 24 so as to provide a fluid tight closure about the valve 8. Since this disc extends outwardly beyond the valve it provides an effective seal which renders impossible oil leakage from within 35 tank 1. The disc 24 is formed of lead, copper 40 or any other suitable material which will serve to effectively seal the valve in the manner stated and yet which is adapted to be ruptured when subjected to appreciable pressure, so as to permit of the contents of the 45 tank 1 being blown out through opening 3.

50 Referring more particularly to Figure 2, it will be noted that the outer face of valve 8 is flat and substantially flush with the outer face of flange 5 so that the sealing disc 24 seats upon the outer face of the valve so as to be held thereby against the external water pressure. In the particular embodiment of 55 my invention illustrated by way of example, the valve 8 opens outwardly and, during its outward opening movement serves to rupture the disc 24 so as to remove all thereof but the peripheral portion clamped between ring 25 and flange 5, thus leaving an unobstructed 60 opening through which the contents of tank 1 can quickly be blown out. I do not, however, limit my invention to use with an outwardly opening valve since, by suitable 65 modifications, it can readily be adapted for use with valves of various types. In its

broader aspects, my invention comprehends a suitable sealing device used in conjunction with a Kingston valve or other valve of like nature, such sealing device being rendered ineffective by opening of the valve.

70

What I claim is:

1. In combination in a submarine boat comprising a hull structure having a fuel receiving tank provided with an opening through the hull to the seat, a valve controlling said opening, and a sealing member in contact with the outer face of the valve and providing a fluid tight closure about the same, said member being rupturable by pressure applied thereto.

75

2. In combination in a submarine boat comprising a hull structure having a fuel receiving tank provided with an opening through the hull to the seat, an outwardly opening valve controlling said opening, and a sealing disc extending beyond the periphery of the valve and forming a fluid tight closure about the same, said disc contacting the outer face of the valve and being adapted to be ruptured by the valve in the outward opening movement thereof.

80

3. In combination in a submarine boat comprising a hull structure having a fuel receiving tank provided with an opening through the hull to the sea, a valve ring secured in said opening, a valve seating in and normally closing said ring, and a sealing disc having its peripheral portion secured to the hull about the valve and forming a fluid tight seal therefor, the disc contacting the outer face of the valve and being adapted to be readily ruptured by appreciable pressure applied upon opening of the valve.

85

4. In combination in a submarine boat comprising a hull structure having a fuel receiving tank provided with an opening through the hull to the sea, a valve ring secured in said opening, an outwardly opening valve seating in and normally closing said ring, and a sealing disc having its peripheral portion secured to the hull about the valve and forming a fluid tight seal therefor, the disc contacting the outer face of the valve and being adapted to be ruptured by the valve in the outward opening movement thereof.

90

5. In combination in a submarine boat comprising a hull structure having a fuel receiving tank provided with an opening through the hull to the sea, a valve ring disposed in said opening and having an outer peripheral flange secured to the hull about the opening, a valve seating in the outer end of the ring, a sealing disc extending over the outer face of the valve in contact therewith, and means cooperating with said flange for clamping the disc about the valve to provide a fluid tight closure therefor, said disc being adapted to be ruptured by pressure applied thereto incident to opening of the valve.

100

6. In combination in a submarine boat

105

comprising a hull structure having a fuel receiving tank provided with an opening through the hull to the sea, a valve ring disposed in said opening and having an outer 5 peripheral flange secured to the hull about the opening, an outwardly opening valve seating in the outer end of the ring, a sealing disc extending over the outer face of the valve in contact therewith, and means cooperating 10 with the flange for clamping the disc about the valve to provide a fluid tight seal therefor, said disc being adapted to be ruptured by the valve in the outward opening movement thereof.

15 7. In combination in a submarine boat comprising a hull structure having a fuel receiving tank provided with an opening through the hull to the sea, a valve ring disposed in said opening and having an outer 20 peripheral flange secured to the hull about the opening, an outwardly opening valve seating in the outer end of the ring with its outer face substantially flush with the outer face of the flange, a sealing disc extending over 25 the outer face of the valve in contact therewith, and means securing the peripheral portion of the disc to said flange and providing a fluid tight closure therebetween, said disc being rendered ineffective by pressure applied thereto incident to opening of the valve.

30 8. In combination in a submarine boat comprising a hull structure having a fuel receiving tank provided with an opening through the hull to the sea, a valve ring disposed in said opening and having an outer 35 peripheral flange secured to the hull about the opening, an outwardly opening valve seating in the outer end of the ring, a sealing disc extending over the outer face of the valve in contact therewith, a clamping ring seating 40 on the outer face of the peripheral portion of the disc, and means for securing the clamping ring to and forcing it toward said flange to effect a fluid tight closure between the 45 flange and the disc, said disc being adapted to be ruptured by the valve during outward opening movement thereof.

In witness whereof, I hereunto subscribe my name this 10 day of June 1929.

50 HUGO E. GRIESHABER.
